United States Patent Office

Des. 212,380
Patented Oct. 8, 1968

212,380

LAMP

Lester Kaehne, 4214 N. Mobile,
Chicago, Ill. 60630

Filed Apr. 11, 1968, Ser. No. 11,411

Term of patent 14 years

(Cl. D48—20)

FIG. 1 is an end elevation view of a lamp constructed in accordance with the invention;

FIG. 2 is a side elevation view of the lamp;

FIG. 3 is an opposite end elevation view of the lamp;

FIG. 4 is a plan view of the lamp;

FIG. 5 is a bottom view of the lamp; and

FIG. 6 is a perspective view of the lamp.

The mesh pattern partially shown on the shade of the lamp is understood to be uniform over substantially the entire surface.

I claim:

The ornamental design for a lamp, substantially as shown and described.
